(57) **CLAIM**

The ornamental design for an ergonomic wireless device, as shown and described.

DESCRIPTION

FIG. 1 is a perspective view of the ergonomic wireless device of the present design.

FIG. 2 is a front view of the ergonomic wireless device of FIG. 1.

FIG. 3 is a rear view of the ergonomic wireless device of FIG. 1.

FIG. 4 is a top view of the ergonomic wireless device of FIG. 1.

FIG. 5 is a bottom view of the ergonomic wireless device of FIG. 1.

FIG. 6 is a left side view of the ergonomic wireless device of FIG. 1; and,

FIG. 7 is a right side view of the ergonomic wireless device of FIG. 1.

1 Claim, 7 Drawing Sheets

FIG. 1

FIG. 2

FIG. 3

FIG. 4

FIG. 5

FIG. 6
